UNITED STATES PATENT OFFICE.

SAMUEL N. SHIELDS, OF GREENSBURG, PENNSYLVANIA.

INSULATED COUPLING.

No. 851,446.

Specification of Letters Patent.

Patented April 23, 1907.

Application filed July 30, 1906. Serial No. 328,385.

To all whom it may concern:

Be it known that I, SAMUEL N. SHIELDS, a citizen of the United States of America, residing at Greensburg, in the county of Westmoreland and State of Pennsylvania, have invented certain new and useful Improvements in Insulated Couplings, of which the following is a specification, reference being had therein to the accompanying drawings.

This invention relates to certain new and useful improvements in insulators, and the invention relates more particularly to an insulator adapted to be used in connection with electrical conduit supports or guy wires.

The invention has for its primary object to provide a simple and inexpensive insulator to which two separate and independent wires or supports may be connected without contacting with one another or passing in close proximity to one another. To this end, I have devised an insulator particularly adapted for the supporting wires of trolley hangers, the insulator being employed to insulate the supporting wires from the poles or standards which support said wires. In this connection, I have devised a block which is preferably made of porcelain or a similar non-conductive material, which is provided with grooves and openings through which open links are adapted to pass, said links being attached to the pole wire or clamped to the trolley supporting wire.

The detail construction entering into my invention will be hereinafter more fully described and claimed, and referring to the drawing accompanying this application, like numerals of reference designate corresponding parts throughout the several views, in which:

Figure 1 is a plan of my improved insulator, Fig. 2 is a cross sectional view taken on the line $x-x$ of Fig. 1, Fig. 3 is a plan of the body portion of my improved insulator, Fig. 4 is a perspective view of an insulator, illustrating a slightly modified form of construction, Fig. 5 is a diagrammatical view illustrating my improved insulator in connection with a trolley pole or standard, and Fig. 6 is a longitudinal sectional view of the insulator illustrated in Fig. 4 of the drawings.

To put my invention into practice, I construct my improved insulator of a rectangular body portion or block 1 said block being made of porcelain or a similar non-conductive material. The block has its sides provided with longitudinally disposed grooves

2, 2 and 3, 3, the grooves 2, 2 at one end of the block being connected by a transverse groove, 4, while the grooves 3, 3 at the opposite end of the block are connected together 60 by a vertically disposed groove 5. In connection with the insulation block just described, I use two open links 6 and 7, each link consisting of a contracted portion 8 a flared portion 9 and parallel eyelets 10. The 65 links are placed in engagement with one another by spreading the eyelets, and then the block 1 is inserted in the flared portion of said links. The links are then drawn outwardly until the contracted portion 8 of the 70 link 6 engages in the grooves 2, 2 of the block 1, while the contracted portion of the link 7 engages in the grooves 3, 3 of said block, the block separating said links, at the same time connecting them one to the other. The 75 links 6 and 7 are preferably made of strong and resilient wire, whereby the links will be slightly sprung when the block is mounted between the contracted portions of said links, thereby preventing the block from becoming 80 disengaged from the links, when not supporting a wire.

In Fig. 5 of the drawing, the application of my improved insulator is illustrated in connection with a trolley pole or standard 11, 85 said pole being provided with a clamping band or strap 12 which engages the eyelets 10 of the link 6, while the eyelets 10 of the link 7 support the end of a wire 14, which is connected to a trolley wire hanger or "mush- 90 room."

In Figs. 4 and 5 of the drawing, I have illustrated a slight modification wherein the grooves 4 and 5 of the block are dispensed with, said block near its one end being provided with a vertically disposed opening 15, while at its opposite end is provided with a transverse opening 16. The sides of the block are provided with grooves 17, 17 which terminate at the ends of the opening 15, while the opposite sides of the block are provided with grooves 18, 18 which terminate at the ends of the opening 16. The wires to be connected to the block pass through the openings 15 and 16, are bent to lie in the grooves 100 17, 17 and 18, 18, whereby the block will form 105 an insulated connecting link between the wires.

While I have herein described the block as being particularly adapted for use in connection with trolley poles and trolley supporting wires, it will be observed that my improved

block, either in the form illustrated in Fig. 3 of the drawing, or in Fig. 4, may be used for connecting wires, especially the wires of a cross over or long curves of a trolley line or electrical conduit.

I do not care to confine myself to the specific shape, size, or details of construction entering into my improved block, as such changes as are permissible by the appended 10 claims, may be resorted to without departing from the spirit and scope of the invention.

What I claim and desire to secure by Letters Patent, is:—

The combination with the insulating body

substantially as described, of a pair of coupling links receiving said block, and each embodying parallel arms connected together at one end and having eyes at their other ends, the said arms being off-set intermediate their ends for a distance substantially equal to the 15 length of the block, substantially as described.

In testimony whereof I affix my signature in the presence of two witnesses:

SAMUEL N. SHIELDS.
